JAMES T. MAHAN, OF AKRON, OHIO

STEREOTYPE CASTING MACHINE

Application filed August 2, 1930. Serial No. 472,504.

The present invention relates to new and useful improvements in stereotype casting machines and particularly to such machines as are used in newspaper or similar work.

5 The object of the invention is to improve upon the design and operation of the machine to secure better and more accurate formation of the plates and to compensate for or rectify inequalities in the matrices.

10 In the operation of casting stereotypes, it is quite frequent for the matrix to be formed inaccurately or to vary in size due to unequal shrinkage, and it is the object of the present invention to redesign the casting machine in such a manner as to compensate for such irregularities in the matrix. The purpose of the invention is secured in an economical and efficient manner as will be more fully explained, it being understood that the invention is not necessarily limited to the detailed construction which has been illustrated herein. Changes and modifications may be made in specific embodiments of the invention without sacrificing any of the benefits thereof.

15 In the drawings in which the best known or preferred form of the invention has been illustrated:

Figure 1 is a vertical section of a stereotype casting machine with the improvements located thereon, the view illustrating the plate cast within the mold, the section of the view being indicated by line 1-1 of Figure 2;

Figure 2 is a plan view thereof;

Figure 3 is a detail view of the supporting and operating means for the apron or pouring sheet;

Figure 4 is an enlarged sectional view taken at the upper edge of the matrix, this view being located at approximately the center of the sheet;

Figure 5 is a similar view taken at or near the edge of the pouring sheet;

Figure 6 is a side view of the lower edge of the apron or pouring sheet;

Figure 7 is a view illustrating the faulty work which is encountered when the matrix is too short and when the pouring sheet is not properly located; and

Figure 8 is a similar view showing the

faulty work done when the matrix is too long and the pouring sheet not properly located.

It has not been thought necessary to illustrate or describe the mechanism of the stereotype casting machine, except insofar as it relates to the invention here described, and it will be understood that such parts as do not directly bear upon the invention have been omitted.

The numeral 1 indicates the fixed head or block which, in the machine illustrated herein, is semi-cylindrical and is water-cooled. The numeral 2 indicates the movable half ring support on which is mounted the half ring 3 which forms the bottom of the pouring or casting cavity and which clamps the matrix 6 at its lower edge, the rear of the matrix being supported by the fixed head.

The numeral 8 represents the movable core which forms the front wall of the cavity.

The matrix extends from the lower half ring to a point along the fixed head and is held and clamped along its upper edge by the pouring sheet or apron 10 which overlaps the upper edge of the matrix just above the marginal rib or bolster 11 formed thereon. For perfect work it is required that the lower edge of the apron 10 meet the rib at the edge of the matrix as shown at *a* in Figure 6 and be slightly spaced therefrom as shown at *b* in the same figure.

In order to secure perfect results in casting of the stereotype plates, it is essential that the edge of the pouring sheet be accurately located with respect to the edge of the matrix, and this result is often not possible where the lower edge of the sheet is always located at fixed points. If the matrix has shrunk too greatly or is not quite long enough, the edge of the matrix will tend to bulge outwardly, as shown in Figure 7, and an imperfect printing edge will be secured along the line *c*. If the matrix be too long, the rib 11 will be flattened by the pouring sheet and in this case also an imperfect printing edge *c* will be obtained, as shown in Figure 8. In the various views, the line to which the plate is cut after casting and cooling is indicated at *d*.

It will be understood that the pouring sheet

or apron is movable into the cavity against the fixed head. Near the upper corners of the pouring sheet are provided the extensions or lugs 15. Through each lug 15 is passed a 5 horizontal shaft 16. A nut 17 on the end of the shaft 16 clamps the pouring sheet in place between blocks or washers 18. Each shaft 16 is rotatably mounted in a sleeve 20 having an angular screw threaded extension 10 21. Fixed on the head are the two brackets 23 in which is located the horizontal shaft 24, the ends of which are extended beyond the brackets on either side of the machine and have fixed arms 25 depending therefrom in alignment with the extensions 21. Turnbuckles 26 connect the parts 21 and 25 and by these means the pouring sheet is suspended, the turnbuckles permitting the 15 length of either or both of the pouring sheet supports to be adjusted. Lock nuts 28 maintain the parts in their adjusted positions.

One of the shafts 16 is provided with the operating handle 30 by which the pouring sheet may be swung into or out of operative 25 position. In order to assist in elevating the pouring sheet, the shaft 24 is provided at one end with an arm 32 to which is attached the spring 33 fixed at its opposite end to a bracket 34 on the head. An adjustable tie-rod 35 may be used to connect the brackets.

By the mechanism which has been described, it is possible to compensate for variations in the length of the matrices and secure 35 perfect castings at all times, the position of the lower edge of the pouring apron or sheet being accurately located by varying the length of the arms 21-25 which support the pouring sheet. It is also possible to tilt the lower edge of the pouring sheet so as to secure the accurate positioning thereof not only 40 along the edge of the sheet, but at the points *a* and *b* as well. The spout for pouring the metal is indicated at 40.

The invention which has been illustrated 45 and described effects a very considerable economy in the operation of stereotype casting machines. It affords a means not heretofore provided for compensating for differences and variations in the matrices. It is 50 very helpful to the casting of perfect printing plates and is a valuable addition to machines of the type and kind illustrated herein. It may also be used to advantage on other forms of casting machines where a pouring 55 sheet or apron is employed.

What is claimed is:

1. A stereotype casting machine comprising a head, a movable core, a matrix support at the base of the cavity between the head and 60 the core, a pouring sheet movable into the cavity, a support from which the pouring sheet is suspended at spaced points so that its lower edge overlaps the matrix, and individually adjustable members on said support whereby the lower edge of the pouring 65

sheet may be located with respect to varying matrices.

2. A stereotype casting machine comprising a head, a movable core, a matrix support at the base of the cavity between the head and 70 the core, a pouring sheet, a support for the pouring sheet, and lengthwise adjustable means for suspending the sheet from the support.

3. A stereotype casting machine comprising a casting cavity, a support for the lower edge of the matrix in the cavity, a sheet adapted to overlap the matrix along its upper edge, shafts to support the sheet adjacent the upper corners thereof, a bearing shaft located above the cavity, and lengthwise adjustable links extending from the bearing shaft to the first named shafts. 75

4. In a stereotype casting machine, a sheet overlapping the upper edge of a matrix in 80 the cavity, a fixed support for the sheet, and variable means for suspending the sheet from the fixed support.

5. In a stereotype casting machine, a sheet overlapping the upper edge of a matrix in 85 the cavity, a fixed support for the sheet, and independently variable means for suspending the corners of the sheet from the fixed support.

6. In a stereotype casting machine, a sheet 90 overlapping the upper edge of a matrix in the cavity, a fixed shaft above the cavity, swinging links on the shaft by which the sheet is suspended, and adjustable mechanism located in said links for varying the 95 effective length thereof.
